UNITED STATES PATENT OFFICE.

MORITZ L. MUELLER, OF SEATTLE, WASHINGTON, ASSIGNOR TO NORTHWEST BLOWER KILN CO., OF SEATTLE, WASHINGTON, A CORPORATION OF WASHINGTON.

METHOD AND APPARATUS FOR KILN DRYING.

Application filed July 20, 1921. Serial No. 486,282.

REISSUED

To all whom it may concern:

Be it known that I, MORITZ L. MUELLER, a citizen of the United States of America, and resident of the city of Seattle, in the county of King and State of Washington, have invented certain new and useful Improvements in Methods and Apparatus for Kiln Drying, of which the following is a specification.

10 My invention relates to dry kilns and the method of operating the same.

The object of my invention is to produce a kiln designed especially for drying lumber but capable of being used for drying other materials, and a method of operating such kilns, which apparatus and method are designed to be an improvement over the existing art.

15 The characteristic feature of the process consists in providing means whereby a positive circulation may be secured in the kiln and whereby a certain small percentage of the air after having passed through the kiln and absorbed moisture from the contents of the kiln, will be discharged from the circulation and its place taken by a like amount of air drawn from an outside source.

Another object of my invention is to provide an apparatus which is simple and cheap 20 in its construction and whereby better and more even distribution and circulation of the air is secured throughout the contents of the kiln.

Other objects of my invention may be seen 25 from a study of the following specification and the accompanying drawings.

The features of my invention which I believe to be new and upon which I desire to secure a patent will be hereinafter disclosed 30 and then particularly pointed out by the claims which terminate this specification.

The accompanying drawings show in a diagrammatic manner the apparatus and the manner of using the same which constitute 35 my invention.

Figure 1 is a plan view of the air distribution system of the kiln, the walls of the kiln being shown in section.

Figure 2 is a longitudinal sectional elevation of that part of the kiln which contains the air distributing pipes.

Figure 3 is a cross sectional view of a kiln having my invention installed therein, illustrating the location of the parts em-

ployed for producing a positive circulation.

Figure 4 is a cross sectional view of a kiln of my construction in which the air distributing pipes are located in somewhat different relation and the manner of circulating the air through the lumber is also somewhat different.

The accompanying drawings show a kiln 1 which is, or may be, in many respects of standard construction. The kiln chamber 65 is shown as being constructed of such size and shape as to receive loaded cars or trucks of lumber for the purpose of drying the same. It is, therefore, provided with track rails 10 which extend through the kiln and 70 upon which lumber piling trucks 11 are mounted to run.

In the device as shown in Figure 3 the lumber is shown as placed horizontally upon the trucks and provided centrally with an 75 opening or chimney 12 which is wider at the bottom than at the top, said chimney preferably tapering from the bottom towards the top. It is to be understood that in forming the piles upon the trucks, cross 80 strips are placed between the layers of lumber thus providing an air circulating passage at each side of each layer of lumber.

In a distributing system having the pipes located and used as is contemplated in Figure 3, the central pipe 2 is the air discharge pipe for the air which is discharged from the heater into the kiln for the purpose of drying the lumber or other product contained therein. The pipe 2 has a large number of discharge slots or holes 20 placed rather closely together and distributed along the length of the pipe. These are in the top wall of the pipe. In consequence, the air discharged through these openings 20 95 is discharged directly into the chimney 12 which has been formed at the center of the load of lumber on the trucks. The air passing up into this chimney passes therefrom laterally in opposite directions between the 100 layers of boards and is discharged at the side of the pipe of lumber, thence flowing downwardly at each side of the kiln and is drawn into the suction or discharge pipes 3 from which it is withdrawn to the heater. 105

The suction pipes 3 are shown as being round in cross section. The round section is however not an essential although it is

a convenience on the score of ease and economy of manufacture. The pipe as a whole is made up of a number of units 30 which are progressively of somewhat smaller diameter as they are located farther away from the point at which said pipe is connected with the suction producing means. As shown in the drawings the connection with both the air supply and the suction pipe is 10 at the center of the length of the kiln. It may, however, be made at any point which has been found suitable and is desirable.

The air discharge pipe 2 is made tapering or decreasing in depth from its main supply 15 pipe 21 in either direction although preferably of uniform width. This pipe is shown as being of polygonal cross section, the same being indicated as a rectangle. The discharge openings 20 are all located in the top 20 wall of the pipe. The suction pipes 3 are shown as being of round cross section. These are progressively smaller in diameter as they are removed from the point where said pipe is connected with the circulation producing 25 mechanism. This reduction in size is shown as being secured by making the pipe up of a number of sections, which sections are progressively of smaller diameter. This difference in diameter is enough so that if 30 the pipe sections be secured to each other along one side, there will be formed between the telescopic ends of the pipe a crescent shaped opening. Such openings are relied upon for passing air into the suction pipe 3.

35 Outside of the kiln is located a heater 4 and a fan 5 or any suitable means for producing a positive circulation of the air. The heater is connected with the air withdrawing or suction pipes 3 of the kiln by means of 40 a flue 30. The fan 5 is connected with the air supply pipes 2 by means of flue 21. The heater and the fan are connected so that the fan draws its air supply from the heater and then forces it into the kiln.

45 The mechanism which is described constitutes one form of closed circulation system for dry kilns. It is not contemplated that this system be operated continuously as a perfectly closed system. I have found that 50 if a small percentage of the air of the kiln be discharged or wasted after it has passed through the dry kiln, it will eventually carry off a very considerable amount of the moisture which has been extracted from the lumber by the heat. The amount of air thus discharged must, however, be replaced. This is done by admitting the required amount of air to the system, preferably at a point just prior to its entrance to the heater 4. For this 55 purpose I have shown in the hood 41 which connects the heater with the suction flue 30, an opening which is normally covered by a slide, as 42. By properly adjusting the slide the opening may be varied in area or entirely closed.

The amount of air drawn into the system at this point should correspond with the amount of air withdrawn from the system at another point or points. By withdrawing a small amount of air and replacing this 70 with air drawn from an outside source, excessive charging of the air in the kiln is prevented and heat units are conserved. I have found it sufficient to provide means for admitting a small amount of air to the heater. 75 As there is a certain amount of suction at this point, this may be done by providing any suitable type of opening which will communicate with the external air.

I have also found that in kilns of normal 80 or usual construction there is sufficient leakage of air, if the pressure inside rises even a quite unappreciable amount, that it is unnecessary to provide special means for the discharge of a small amount of air from the 85 kiln. For this reason I have not shown any special air discharging means except as the flue 13 serves for this purpose. Special discharge openings of any suitable type may be provided if this is thought desirable. As 90 kilns are usually constructed natural leakage will be found sufficient.

In the kiln as illustrated in Figure 4 the lumber trucks are supposed to be loaded with lumber which has been piled on edge. 95 In this case I prefer to reverse the locations of the air supply and discharge pipes. In this case I prefer to have the air supply pipe divided, one being placed at each side close against the wall of the kiln. The air suction 100 pipe or that which is used to withdraw air from the kiln is in this case located centrally beneath the kiln. In such case as this the hot air discharged from the fan is blown upwardly into the passageways existing between the sides of the load and the side walls of the kiln. This air enters between the lumber at the top of the pile and is drawn downwardly and into the air discharge pipe 3. The position of these pipes may be shifted 105 as is thought best for different methods of piling the lumber.

110 Experience has shown that the air distributing means employed secures a substantially uniform distribution of air throughout the length of the kiln. Also that by continuously withdrawing the lumber and replacing this with unsaturated air, the necessity for condensing the moisture is eliminated. This retains the heat in the air except for the 115 small amount contained in the discharged air and thus produces economy in operation.

120 What I claim as my invention is:

1. In combination a kiln, a lumber car trackway therein, a discharge conduit centrally disposed beneath the trackway and having a plurality of openings in its upper side, said conduit being gradually reduced in height from an intermediate portion toward its opposite outer ends, suction con- 125

duits having a plurality of inlet openings disposed upon opposite sides of the trackway and gradually reduced in capacity from an intermediate portion toward their ends, 5 a circulating fan and casing therefor, and conduits connecting one side of said fan casing to the suction conduits and the other side of said fan casing to the discharge conduit said suction units being composed of 10 a plurality of successively smaller circular sections the joints of which are so loosely fitted as to permit the passage of air into said conduit at said joints.

2. The herein described improvement in 15 the art of drying lumber in a kiln having a trackway extending longitudinally thereof and an air discharge conduit lying between the rails of the track and extending in substantial parallelism therewith, and provided 20 with openings discharging air under pressure upwardly at a number of points

in its length, which improvement consists of piling lumber upon trucks with the successive layers of lumber spaced from each other to leave a plurality of lateral air 25 passages therebetween, said lumber being so piled as to leave a longitudinally elongated central flue in each pile of lumber which is constricted upwardly and substantially closed at the top to thereby cause air delivered into the lower part of said flue to pass through said lateral openings and introducing said trucks into said kiln upon the tracks so that air from the air discharge 30 conduit will be delivered into the elongated 35 flues of the piles of lumber at whatever point upon the trackway they may be positioned.

Signed at Seattle, King County, Washington, this 15th day of July, 1921.

MORITZ L. MUELLER.
